UNITED STATES PATENT OFFICE.

EDWARD W. KELLOGG AND CHESTER W. RICE, OF SCHENECTADY, NEW YORK, AS-
SIGNORS TO GENERAL ELECTRIC COMPANY, A CORPORATION OF NEW YORK.

RADIO RECEIVING SYSTEM.

Application filed May 18, 1921. Serial No. 470,712.

To all whom it may concern:

Be it known that we, EDWARD W. KELLOGG and CHESTER W. RICE, citizens of the United States, residing at Schenectady, in the county of Schenectady, State of New York, have invented certain new and useful Improvements in Radio Receiving Systems, of which the following is a specification.

Our present invention relates to radio receiving systems, and more particularly to receiving systems by means of which signaling waves from a desired direction may be received without interference from disturbing waves coming from other directions.

One of the objects of our invention is to provide in conjunction with the unidirectional horizontal receiving antenna, a simple and efficient means whereby the receiving station may be located at any desired point along the length of the antenna, which may be at some distance from the point in the antenna at which the desired signaling currents are strongest.

In our prior application, Serial No. 372, 25 938, filed April 10, 1920, we have described a receiving antenna which will have marked unidirectional properties. In this case a long horizontal antenna is employed which extends preferably in the general direction 30 of transmission of the signals to be received, and which preferably has a length of at least the order of magnitude of a half wave length of the signal to be received. In case such an antenna is properly constructed signals coming from a desired station will be found to be strongest at the end of the antenna which is farthest from the transmitting station while signals coming from the opposite direction will be very weak at that 40 end.

In our prior application above referred to we have indicated methods whereby the desired signaling currents may be conveyed by a transmission line from a point in the antenna where they are strongest, to a receiving station located at some distance from the antenna. A more specific object of our present invention is to provide means whereby the receiving station may be located at a point along the length of the antenna distant from the point at which the desired signals are strongest, and whereby the desired signals may be transmitted to the receiving apparatus over a transmission line 50 extending parallel with the antenna without

interfering with the desired operation of the receiving system. Another object is to provide means for protecting the antenna from waves built up in near by wires such as telephone or power lines.

60

The novel features which we believe to be characteristic of our invention are set forth with particularity in the appended claims. The invention itself, however, both as to its organization and method of operation, together with further objects and advantages thereof, will best be understood by reference to the following description taken in connection with the accompanying drawing in which Figs. 1, 2 and 3, respectively show 70 diagrammatically three different arrangements whereby our invention may be carried into effect.

65

As indicated in Figs. 1 and 2, we provide a long horizontal antenna made up of two 75 parallel conductors 1 and 2 the opposite ends of which are grounded at 3 and 4. This antenna is preferably so constructed and its constants so adjusted that the current wave therein will travel along its length at the 80 same velocity as the signaling wave in space so that the current wave will gradually grow in amplitude as it travels along the conductor. If it is desired to receive a signal which approaches the antenna from the end 3, the 85 amplitude of the current set up in the antenna at 3 by the desired wave will be extremely small while at the end 4 the amplitude of the desired currents will be a maximum. It may, however, in some cases, be 90 more convenient to locate the receiving station at some point along the antenna distant from the end 4, as for example, at the end 3 of the antenna. To permit of such location 95 of the receiving station we may provide, as shown in Fig. 1, a transmission line made up of two conductors 5 and 6 extending parallel with the antenna conductors 1 and 2. This transmission line may be supported upon the same poles as the antenna conductors. The transmission line is coupled to the 100 end 4 of the antenna by means of a coupling transformer 7. It will be apparent that when arranged in this way the transmission line itself will also act as an antenna and that currents will be produced therein by waves traveling in both directions. The currents produced by ether waves acting directly upon the transmission line flow through the 105 two conductors thereof in the same direc-

110

tion while currents impressed upon the transmission line by the transformer 7 will flow through the two conductors in opposite directions. In order to prevent the currents produced in the transmission line acting as an antenna from being impressed upon the receiving apparatus 8, the mid points of the secondary of the transformer 7 and the primary of the transformer 9 by means of which the desired signaling currents are impressed upon the receiving apparatus, are grounded through damping resistances 10 and 11, so that any currents which may be received upon the transmission line will flow in opposite directions through the two halves of these transformer windings and will produce equal and opposite effects upon the secondary of transformer 9. As a result the receiver will be unaffected by such currents.

20 The end 3 of the antenna is also preferably grounded through a resistance 12, approximately equal to the surge impedance of the antenna so that no reflection can occur from this end of the antenna, and therefore no currents will be transferred to the transmission line from waves traveling from the end 4 toward the end 3 of the antenna.

If the transmission line is constructed so as to have the same velocity of propagation as that of electromagnetic waves in space so that currents produced therein by waves traveling in either direction will build up to a large value, such currents may under some conditions induce in the antenna conductors undesired currents which travel in the antenna conductors in the same direction as the desired signaling currents. This difficulty may be avoided by providing a plurality of loading coils 13 in the transmission line. By this means the velocity of propagation of the currents in the transmission line may be reduced to such an extent as to prevent waves of an appreciable magnitude being built up in the transmission line. The difference in velocity of the currents in the transmission line and in the antenna will also tend to reduce the interchange of energy between the two circuits. The distances between adjacent loading coils in each of the line conductors should preferably be considerably less than half a wave length of the shortest wave to which the receiving apparatus is sensitive.

With the arrangement thus far described, it will be apparent that the velocity of propagation of the transmission line may be reduced both for undesired currents and for the desired signaling currents. It may, however, be desirable that the velocity of propagation of the signaling currents shall be unaffected, and since these currents flow in opposite directions through the two conductors of the transmission line, the effect of the loading coils for such currents may be neutralized by coupling the coils of opposite

sides of the transmission line together in such a way that the magnetic fields of the two coils oppose for currents flowing in opposite directions in the two conductors, and add for currents flowing in the same direction in the two conductors.

70 In Fig. 2 we have indicated another method by means of which similar results may be obtained. In this case the transmission line is divided into sections by means of 75 transformers 14 and 15, the length of each section being considerably less than one half of the shortest wave length to which the receiving apparatus is sensitive. These transformers permit of the ready transfer of desired signaling currents, but will not transfer currents flowing in the same direction in the two conductors.

80 In some cases it may be desirable to employ the transmission line for transferring 85 currents of audio or signaling frequency from one point to another. One manner in which the transmission line may be constructed in this case so as to prevent the building up therein of undesired high frequency currents is indicated in Fig. 3. In 90 this case we have indicated a transmission line conveying signaling currents from terminal apparatus 16 to the receiving apparatus 8. Inductances 17, which will offer a 95 comparatively low impedance to the signaling currents and a high impedance to high frequency currents, may be inserted in the transmission line, and these inductances may be shunted by high resistances 18, which will 100 absorb the energy of the high frequency currents. Similarly, the high frequency currents may be caused to leak off to the ground connections at 19 through small capacity condensers 20, and resistances 21. 105 The condensers 20 will offer a low impedance to the high frequency but a high impedance to the signaling current so that but little of the signaling current will flow through the connection thus established between the two sides of the transmission line.

110 While we have shown methods of preventing disturbances on an antenna resulting from the proximity of wires used as a transmission line in conjunction with the radio receiving system, it is evident that the same methods may be applied to preventing disturbances in an antenna of the type we have described resulting from the proximity of parallel wires used for entirely different purposes, such as telephone, telegraph or power conductors.

115 While we have shown and described the preferred embodiments of our invention it is apparent that our invention is by no means limited to the particular arrangements described but that many modifications therein may be made without departing from the scope of our invention as set forth in the appended claims.

What we claim as new and desire to secure by Letters Patent of the United States, is:—

1. A receiving system for radio signals comprising a long horizontal receiving antenna, a transmission line running parallel to said antenna for conveying signaling currents from a selected point in said antenna to a distant receiving station, and means for preventing undesired inductive effects between the antenna and the transmission line. 5
2. A receiving system for radio signals comprising a long horizontal receiving antenna, a transmission line running parallel to said antenna for conveying signaling currents from a selected point in said antenna to a distant receiving station, the constants of said transmission line being so adjusted that the velocity of propagation of currents transmitted thereby is less than the velocity 15 of propagation of currents in the antenna. 20
3. A receiving system for radio signals comprising a long horizontal receiving antenna, a transmission line running parallel to said antenna for conveying signaling currents from a selected point in said antenna to a distant receiving station, the constants of said transmission line being so adjusted as to prevent undesired waves of appreciable magnitude being built up therein. 25
4. A receiving system for radio signals comprising a long horizontal receiving antenna, a transmission line running parallel to said antenna for conveying signaling currents from a selected point in said antenna to a distant receiving station, and a plurality of loading coils inserted in said transmission line. 30
5. A receiving system for radio signals comprising a long horizontal receiving antenna, a transmission line made up of two parallel conductors running parallel to said antenna for conveying signaling currents from a selected point in said antenna to a distant receiving station and means for preventing undesired inductive effects between the antenna and the transmission line. 40
6. A receiving system for radio signals comprising a long horizontal receiving antenna, a transmission line made up of two parallel conductors running parallel to said antenna for conveying signaling currents from a selected point in said antenna to a distant receiving station, the constants of said transmission line being so adjusted that the velocity of propagation of currents transmitted thereby is less than the velocity of propagation of currents in the antenna. 50
7. A receiving system for radio signals comprising a long horizontal receiving antenna, a transmission line made up of two parallel conductors running parallel to said antenna for conveying signaling currents from a selected point in said antenna to a distant receiving station, the constants of said transmission line being so adjusted as to 55
8. A receiving system for radio signals comprising a long horizontal receiving antenna, a transmission line made up of two parallel conductors running parallel to said antenna for conveying signaling currents from a selected point in said antenna to a distant receiving station, and a plurality of loading coils inserted in said transmission line. 75
9. A receiving system for radio signals comprising a long horizontal receiving antenna, a transmission line made up of two parallel conductors running parallel to said antenna for conveying signaling currents from a selected point in said antenna to a distant receiving station, and a plurality of loading coils inserted in said transmission line, said loading coils being so arranged that the velocity of propagation of currents traveling in the same direction through the two conductors of said transmission line is less than the velocity of propagation of currents traveling in opposite directions through the two conductors. 80
10. A receiving system for radio signals comprising a long horizontal receiving antenna, a transmission line made up of two parallel conductors running parallel to said antenna for conveying signaling currents from a selected point in said antenna to a distant receiving station, and a plurality of loading coils inserted in said transmission line, the loading coils in one side of said transmission line being inductively associated with the loading coils in the other side of the transmission line. 90
11. A receiving system for radio signals comprising a long horizontal receiving antenna, a transmission line running parallel to said antenna, the constants of said transmission line being so adjusted that the velocity of propagation of currents transmitted thereby is less than the velocity of propagation of currents in the antenna. 100
12. A receiving system for radio signals comprising a long horizontal receiving antenna, a transmission line running parallel to said antenna, the constants of said transmission line being so adjusted as to prevent undesired waves of appreciable magnitude being built up therein. 110
13. A receiving system for radio signals comprising a long horizontal receiving antenna, a transmission line running parallel to said antenna, and a plurality of loading coils inserted in said transmission line for preventing undesired inductive effects between the antenna and the transmission line. 120
14. A receiving system for radio signals comprising a long horizontal receiving antenna, a transmission line made up of two parallel conductors running parallel to said antenna the constants of said transmission line being so adjusted as to 125

- line being so adjusted that the velocity of propagation of currents transmitted thereby is less than the velocity of propagation of currents in the antenna.
5. 15. A receiving system for radio signals comprising a long horizontal receiving antenna, a transmission line made up of two parallel conductors running parallel to said antenna, the constants of said transmission line being so adjusted as to prevent undesired waves of appreciable magnitude being built up therein.
- 10 16. A receiving system for radio signals comprising a long horizontal receiving antenna, a transmission line made up of two parallel conductors running parallel to said antenna, and a plurality of loading coils inserted in said transmission line for preventing undesired inductive effects between the antenna and the transmission line.
- 15 17. A receiving system for radio signals comprising a long horizontal receiving antenna, a transmission line made up of two parallel conductors running parallel to said
- antenna and a plurality of loading coils inserted in said transmission line, said loading coils being so arranged that the velocity of propagation of currents traveling in the same direction through the two conductors of said transmission line is less than the 25 velocity of propagation of currents traveling in opposite directions through the two conductors.
18. A receiving system for radio signals comprising a long horizontal receiving antenna, a transmission line made up of two parallel conductors running parallel to said antenna, and a plurality of loading coils inserted in said transmission line, the loading coils in one side of said transmission line being inductively associated 30 with the loading coils in the other side of the transmission line.
- 35 40

In witness whereof, we have hereunto set our hands this 17th day of May, 1921.

EDWARD W. KELLOGG.
CHESTER W. RICE.
